TIE RACK

William Grant Williams, Anaheim, Calif.

Application January 24, 1949, Serial No. 432

Term of patent 14 years

(Cl. D33—8)

To all whom it may concern:

Be it known that I, William Grant Williams, a citizen of the United States, residing at Anaheim, in the county of Orange and State of California, have invented a new, original, and ornamental Design for a Tie Rack, of which the following is a specification, reference being had to the accompanying drawings forming part thereof.

Figure 1 is a top plan view of the tie rack embodying my new design, in collapsed position;

Fig. 2 is a view in front elevation of the same;

Fig. 3 is a view in end elevation of the same;

Fig. 4 is a top plan view similar to Fig. 1, but showing the tie rack in expanded or extended position;

Fig. 5 is a view in front elevation of the same.

I claim:

The ornamental design for a tie rack, as shown.
WILLIAM GRANT WILLIAMS.
